UNITED STATES PATENT OFFICE.

ZENON P. LEGER, OF MONCTON, NEW BRUNSWICK, CANADA.

WHEEL-LOCKING DEVICE.

1,302,681.

Specification of Letters Patent.

Patented May 6, 1919.

Application filed June 25, 1918. Serial No. 241,823.

To all whom it may concern:

Be it known that I, ZENON P. LEGER, a subject of the King of Great Britain, residing at Moncton, Province of New Brunswick, Canada, have invented certain new and useful Improvements in Wheel-Locking Devices; and I do hereby declare that the following is a full, clear, and exact description of the invention, such as will enable others skilled in the art to which it appertains to make and use the same.

The present invention relates to devices to be used in connection with freight cars and other rolling stock when changing the brasses therefor, and more particularly to a device for clamping and locking the wheels of the car to the rails, so as to prevent the wheels from rising when lifting the weight of the trucks which bears upon the axles.

An object of the present invention is to provide an apparatus of this character which may be easily and readily applied or removed from the wheel, and one which will be strong, durable and efficient in use and comparatively inexpensive in the cost of manufacture.

With the above and other objects in view which will hereinafter appear as the description continues, the invention consists of the novel features of construction, combination and formation of parts as will be hereinafter more fully described and particularly pointed out in the appended claim.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the scope of the claim without departing from the spirit of the invention or sacrificing the efficiency of the same.

In the accompanying drawings:

Figure 1 is a detail perspective view of the device embodying the present invention as applied to the wheel of a car for locking the same to the rail of the track.

Fig. 2 is a side elevation of the same;

Fig. 3 is an enlarged detail section through the bearing blocks of the car;

Fig. 4 is an enlarged detail end view of

one of the clamping plates when connected to the rail of the track;

Fig. 5 is a detail side elevation of the locking connection between the ends of the chain; and,

Fig. 6 is a detail sectional view through the same.

Referring now more particularly to the accompanying drawings wherein like and corresponding parts are designated by similar reference characters throughout the several views.

The numeral 1 indicates an ordinary rail of a track over which are adapted to pass the wheels 2 of a car which are carried by the axles 3. The truck 4 of the car carries the usual bearing blocks 5 and arranged between the axles 3 and these bearing blocks are the usual brasses 6. These brasses 6 wear out very often and to replace the same it is necessary to raise the truck 4 by means of the jack 7 so as to release the weight of the truck from the axle 3. When the truck has been raised the brasses 6 may be easily removed and new ones substituted therefor should they become worn or broken. In so raising the trucks the wheels and axles thereof have a tendency to rise from the tracks 1, thereby causing their derailment and to lock the wheels upon the rails so as to prevent the same from rising or moving when changing the brasses, I provide the locking device embodying the present invention which will now be described.

This locking device comprises two clamps indicated by the numeral 8 which engage the rails 1 and connected to each of these clamps is the opposite end of a chain, which latter comprises the sections 9 and 10 respectively. This chain comprises the usual links, but the section 9 is provided with a link 11 which is provided with an enlarged portion and a narrow portion 12. In adjusting the length of this chain the section 10 may pass through the enlarged portion of the link 11, but when it is slipped within the narrow portion 12 of this link 11, the sections of the chain will be securely locked together. The clamps 8 each comprise a plate having a recess therein for receiving the ball of the rail and these plates are provided with the depending portions 12 and 13 which extend on each side of the rail and the depending portion 13 is provided with a lip 14 which extends under the ball of the

5 rail. By providing clamps of this construction it is obvious that they may easily and readily be placed upon the ball of the rail and the chain may be placed over the
5 tire of the wheel as better illustrated in
10 Figs. 1 and 2. By adjusting the chain the wheel will be securely clamped or locked to the rail, thereby preventing the same from rising or moving when jacking up the
15 truck of the car. The recesses formed within these clamps 8 are made to be placed over the standard size rail, but these recesses may have a width greater than the width of the ball of the rail so as to enable the same
15 to be placed upon rails of various sizes, and when putting such clamps to rails of smaller sizes suitable wedges may be inserted between the depending portion 12 of the clamp and the ball of the rail.

Copies of this patent may be obtained for five cents each, by addressing the "Commissioner of Patents, Washington, D. C."

Having thus fully described my invention, what I claim as new and desire to secure by Letters Patent is:

A device of the character described comprising a pair of clamps, each of said clamps comprising a plate having a pair of spaced 25 depending portions, one of said depending portions having a lip extending inwardly at right angles to said last mentioned depending portion and the other depending portion extending outwardly at an angle to said lip 30 forming an opening therebetween adapted to receive the ball of a rail, and means connected to opposite ends of said clamps adapted to pass over the rim of a car wheel.

In witness whereof I have hereunto set 35 my hand.

ZENON P. LEGER.
